UNITED STATES PATENT OFFICE.

HARRY SPURRIER, OF DETROIT, MICHIGAN, ASSIGNOR OF ONE-HALF TO HENRY M. LANE, OF DETROIT, MICHIGAN.

DETERGENT.

No Drawing.

Application filed May 31, 1921. Serial No. 473,823.

To all whom it may concern:

Be it known that I, HARRY SPURRIER, a citizen of the United States, residing at Detroit, in the county of Wayne and State 5 of Michigan, have invented certain new and useful Improvements in Detergents, of which the following is a specification.

This invention relates to detergents; and it comprises as a new detergent material an 10 intimate mixture of neutral soap and mechanical wood pulp: all as more fully hereinafter set forth and as claimed.

Engine grease, used lubricating oil and the like are virtually oily suspensions with 15 extremely fine carbon, metal, etc., as the suspensoid; the dirt being, so to speak, col- loided by the oil and being enclosed and protected thereby. In removing dirty 20 greasy matter from the skin with soap and water the oil is converted into an emulsion and removed as such; and as it clings firmly, more or less friction is necessary to detach 25 it from its wetting contact and substitute the soapy solution in its place. For this reason in making soapy compositions for removing greasy dirt, it is usual to employ a filler of a more or less granular material 30 of some kind; usually sand, kieselguhr or something of that sort having an abrading 35 function. An arbradant is used since the surface of the skin is not smooth and it is necessary to reach the grease in the furrows. Such compositions however are disagreeable to use; and particularly if the use be re- peated within short time intervals.

In the present invention I accomplish the result of detaching the grease from the furrows and rugosities of the skin by the use, 40 in conjunction with the soap, of an ex- tremely fine, purified, wood fiber of the type of that known as "mechanical pulp" and used for making low grade paper. These 45 fibers can be obtained fine enough to enter the tiny skin furrows and, so to speak, mop up the greasy matter so it will emulsify, while they are too soft to have any of the objectionable abrading action. The pulp, moreover, has a wonderful emulsifying power of its own in promoting the suspen- 50 sion of oil in soap solutions. Mechanical pulp is made by presenting wood end-on to a rapidly rotating grindstone in the presence of a flow of water and the fibers so made

are not sharp ended or slivery and are very fine. Moreover, most of the resins and 55 glucosides are thereby removed. Chemical pulps and sawdust do not have these desirable properties and are not adapted for the present purpose. Mechanical wood pulp fibers neither abrade nor pierce the skin. 60

I find that a mixture of a good neutral soap with a small proportion of mechanical wood pulp fibers quickly removes used 65 lubricating oils and similar matters from the skin, without substantial abrasion or 70 injury of the skin. The wood pulp fibers are finer than the skin furrows and in such furrows act like so many minute soft sponges, wiping off the oil and included suspensoids so that the oil can be suspended 75 in the soap solution.

The mechanical pulp used should be of a very finely divided type and it is best made from poplar or aspen wood. With 80 these woods the fiber is of such a character 75 that it cannot act in any way like a sliver. In connection with soap and water the fibers act, so to speak, as a series of wash rags or towels which go into the irregularities of 85 the skin and mop up the dirt.

Mechanical wood pulp may be used in connection with any of the usual soaps of the usual compositions provided they are 90 free from included abradants, sawdust, etc. A formula which gives excellent results is 85 made with 300 parts of run soap taken directly from the kettle, 800 parts of water and 100 parts of mechanical wood pulp (best poplar or aspen). Sufficient dye or color- 95 ing matter may be used to give the desired color. Perfume may be used if desired.

What I claim is:—

1. As a detergent, a composition substan- tially consisting of mechanical wood pulp and neutral soap free from abradants. 95
2. As a detergent, a composition substan- tially consisting of mechanical poplar wood pulp and neutral soap free from abradants.
3. As a detergent, a composition substan- tially consisting of 300 parts of run soap, 100 800 parts of water and 100 parts of wood pulp.

In testimony whereof, I have hereunto affixed my signature.

HARRY SPURRIER.
